UNITED STATES PATENT OFFICE.

GODFREY ENGEL, OF BALTIMORE, MARYLAND.

SUGAR-CRYSTALLIZER.

SPECIFICATION forming part of Letters Patent No. 759,686, dated May 10, 1904.

Application filed May 1, 1901. Serial No. 58,276. (No model.)

To all whom it may concern:

Be it known that I, GODFREY ENGEL, a citizen of the United States, residing at Baltimore, State of Maryland, have invented certain new and useful Improvements in Crystallizers; and I do hereby declare the following to be a full, clear, and exact description of the invention, such as will enable others skilled in the art to which it appertains to make and use the same.

10 My invention relates to improvements in crystallizers employed in the manufacture of sugar to extract sugar from molasses and the like.

15 My invention consists in the novel means employed for heating or cooling the contents of the crystallizer and for setting up circulation of the fluid therein and in the novel manner of closing the stirring-arms and connecting the stirring-blades thereto.

20 The objects of my invention are to improve the construction of crystallizers to render the same more efficient, to produce effective circulation of the contents of the crystallizer by the action of the revolving stirring-arms, and 25 to simplify and cheapen the construction of the crystallizer. These objects are attained in the invention herein described, and illustrated in the drawings which accompany and form a part of this specification, in which the same 30 reference-numerals indicate the same or corresponding parts, and in which—

Figure 1 is a central vertical section of one form of crystallizer constructed in accordance with my invention, the stirring-blades being 35 arranged in the form of spirals, so as to produce endwise circulation of the contents of the crystallizer. Fig. 2 is a corresponding view of another form of crystallizer, in which the stirring-blades are not arranged in the form 40 of a spiral. Fig. 3 is an end view of the crystallizer, showing the driving mechanism. Fig. 4 is a transverse section of the hollow shaft and a side view of two of the stirring-arms, showing how said arms are closed at their ends and 45 showing how the stirring-blades are attached to said arms; and Fig. 5 is a longitudinal section of a portion of the hollow shaft, likewise showing how the stirring-arms are closed at the ends and how the stirring-blades are connected to said arms.

In the drawings, 1 indicates a chamber, formed of boiler-plate or other suitable material and preferably cylindrical in shape. It is provided with suitable manholes, through which crystallized sugar may be removed and 55 through which workmen may enter when necessary, and with a supply-pipe 2, a discharge-pipe 3, and a hollow stirrer-shaft 4, having bearings in the ends of the chamber and provided with stuffing-boxes at its ends to permit 60 the connection to it of pipes 5 and 6, through which hot or cold fluid or vapor may be admitted to its interior and circulated through it. Upon shaft 4 there is also a worm-wheel 7, intermeshing with a worm 8 (indicated in dotted 65 lines in Fig. 3) upon a shaft 9, carrying belt-wheels by which said shaft, and therefore the shaft 4, may be driven.

The shaft 4 is provided with a plurality of projecting stirring-arms 10. These arms are 70 preferably formed of pipe, are screw-threaded at one end to permit them to be connected to shaft 4, and at the other end are closed by flattening and welding together their sides, all as shown in Figs. 4 and 5. The flattening 75 and welding together of the sides of these tubes not only closes their ends securely, but the flattened portion so formed makes an excellent seat for the stirring-blades to be connected to such arms.

11 11 in Fig. 1 and 11' 11' in Figs. 2, 4, and 5 indicate the stirring-blades. When it is desired to produce circulation of the fluid from one end of the vessel to the other, the arms 10 may be arranged upon the shaft 4 in spirals, the blades 11 then becoming spiral stirring-blades, as shown in Fig. 1, which not only agitate the contents of the crystallizer, but produce endwise circulation, acting in this 85 respect like propeller-blades; but when such 90 endwise circulation is not necessary the arms and stirring-blades may be arranged as shown in Fig. 2.

Since the arms 10 are hollow and are in communication with the interior of the hollow 95 shaft 4, through which, as already stated, hot or cold fluid or vapor may be circulated, they form heating or cooling arms, as the case may be, transmitting heat to or conducting heat from the contents of the crystallizer, and 100

therefore serving to regulate the crystallization of the sugar from the solution. Because these arms are constantly moving through the fluid in the evaporator they are very efficient 5 in heating or cooling such fluid, heating or cooling all parts alike. The number of stirring-arms may be varied as desired and may be less or greater than the number shown in the accompanying drawings.

- 10 In the extraction of sugar the sugar-bearing solutions are evaporated in vacuum-pans, and the sugar is thereby caused to crystallize out of the solution until, because of the low sugar content of the solution or the presence 15 of impurities, the sugar will no longer crystallize in the vacuum-pans. The solution is then passed into crystallizers, which may be divided into one or more groups according to the quality of the product to be obtained. In 20 these crystallizers the crystallization of the sugar is continued under conditions of temperature and viscosity produced by the operation of the crystallizers.

If conditions permit, sugar crystallizes at 25 the point of saturation of the solution. The object of stirring the solution and of heating or cooling it, as the case may be, is to produce the desired favorable conditions.

If the sugar solution treated be a relatively 30 high testing solution, the sugar tends to crystallize relatively rapidly in the crystallizer, and the solution should be cooled more rapidly than will be accomplished by simple radiation of heat through the walls of the crystallizer 35 to the surrounding atmosphere. When such solutions are treated, therefore, a cooling fluid, such as cold water, should be circulated through the pipe 4 and stirring-arms. Instead of cold water a brine solution, kept cold 40 by ice or by the operation of a refrigerating-machine, may be used or ammonia or other suitable gas under pressure may be expanded in the shaft 4 and stirring-arms.

If the solution treated be a relatively low

testing solution, the sugar crystals form more 45 slowly, and it is necessary to cause the solution to cool somewhat more slowly than would be accomplished by radiation to the surrounding atmosphere. Hot water or steam may be circulated through the pipe or shaft 4 and 50 stirring-arms in such case.

My improved crystallizer may also be employed as an evaporator or drier for the treatment of many substances.

Having thus completely described my invention, what I claim, and desire to secure by Letters Patent, is—

1. In an apparatus of the class described, the combination, with a suitable chamber, of a hollow stirrer-shaft therein, provided with 60 means by which fluid or vapor may be admitted to it, and provided likewise with projecting pipe-arms, communicating with the interior of the stirrer-shaft, and therefore adapted to receive the heating or cooling fluid or vapor 65 within said shaft, said arms being flattened and having their sides welded together, at their outer ends, whereby said arms are closed and seats are formed for a stirrer-blade, a stirrer-blade secured to the flattened portions 70 of said arms, and means for rotating the stirrer-shaft.

2. In an apparatus of the class described, the combination, with a suitable chamber, of a hollow stirrer-shaft therein, provided with 75 means by which fluid or vapor may be admitted to it, and provided likewise with projecting pipe-arms, arranged spirally about said shaft and communicating with the interior thereof, adapted to receive the heating or cool- 80 ing fluid or vapor within said shaft.

In testimony whereof I affix my signature in the presence of two witnesses.

GODFREY ENGEL.
